UNITED STATES PATENT OFFICE.

GEORGE R. GORNWALL, OF RYE, NEW YORK, ASSIGNOR TO AMERICAN PLANOGRAPH COMPANY, A CORPORATION OF WEST VIRGINIA.

ART OF PRINTING.

1,086,897.

Specification of Letters Patent. Patented Feb. 10, 1914.

Application filed May 29, 1905, Serial No. 262,818. Renewed July 12, 1913. Serial No. 778,774.

To all whom it may concern:

Be it known that I, GEORGE R. GORNWALL, a citizen of the United States, residing at Rye, in the county of Westchester and State 5 of New York, have invented new and useful Improvements in the Art of Printing, of which the following is a specification.

The invention relates to the printing art and has for an object to provide a surface 10 and a composing device which will permit of the production of justified lines of printing from direct composition without any preliminary representation or calculation, as have heretofore been necessary in the art, 15 and without distortion or change of relation of the characters in any word or group.

A further object of the invention is to produce a line unit capable of producing the result indicated.

20 These and other objects will in part be obvious and will in part more fully appear from the following description.

The accompanying drawings, referred to herein and forming a part hereof, illustrate 25 one embodiment of the invention, the same serving in connection with the description herein to explain the principles of the invention.

Of the drawings: Figure 1 represents a 30 surface of the character contemplated by this invention; Fig. 2 is an edge view of such a surface; Fig. 3 shows a surface with a series of groups of characters impressed thereon; Fig. 4 shows such a surface with 35 cuts therein between the groups of characters; Fig. 5 represents such a surface with a cut or slit therein; Fig. 6 shows an elevation of a line bar having a character-receiving surface of the kind contemplated by 40 this invention; Fig. 7 is an end elevation of the line bar shown in Fig. 6; Fig. 8 is a detail showing a modified form of holding means; and Fig. 9 shows the arrangement 45 of the characters upon the elastic surface.

This invention has in view, as above indicated, the production of composed matter 50 so that such matter will represent justified lines from direct composition without preliminary justification of an entire line, preliminary representation of any character, such as a dummy line, a perforated strip, etc., as has been heretofore necessary in the art.

The invention contemplates the providing

of a character receiving medium consisting 55 of two layers one of said layers being of elastic material and the other layer of inelastic material and further contemplates the providing of such material in such form as may be best suited for the particular work 60 to be done.

In certain aspects of the invention, it is contemplated to provide a material in line units, and in such form as to give a justified line with ease, certainty and celerity. 65

Other features of the invention are pointed out elsewhere herein.

In the drawings the character-receiving surface of the character-receiving medium is indicated by 1. The said member 1 consists of any substantially inelastic material, such as paper or metal, and also being capable of receiving an impression from types or other imprinting means. The said surface may be of such nature also as to lend 70 itself to some process of reproduction, as by photography, contact transfer, offset printing, etc. The said member 1 in the present embodiment may be fastened to the member 2 of the said character-receiving 75 medium by any proper means such as glue, cement, etc. The member 2 consists of any suitable elastic medium, such as rubber. It is immaterial whether the character-receiving surface be the elastic or inelastic member, and each form is shown in the drawings herewith. The members 1 and 2 together constitute the character-receiving medium 80 85 3. Upon the character-receiving surface 1 a series of characters may be imprinted, such characters generally constituting composed matter and being grouped into words or syllables. A surface bearing such a series of grouped characters is shown in Fig. 3.

In Fig. 4 is shown the character-receiving 90 medium with cuts 4 made through the member 1, while the member 2 is left intact. It is obvious that if tension be applied to one end of the medium while the other end remains stationary, that the elastic medium 100 will elongate at those points where the inelastic material has been cut through, while the inelastic material, by reason of its nature and of its being cut through at several points between the point where the medium 105 3 is stationary and the point where tension is applied, will move with the elastic material but without suffering any deformation what-

soever. The line may thus be extended so as to be justified to the predetermined measure and the elongation of the line will take place entirely in the cuts 4, *i. e.*, be inter-
5 verbal, thus accomplishing the desired result without distortion, or change of relation of the characters in any group.

In Fig. 5 of the drawings a strip carrying a printed line is shown wherein the inelastic 10 material has been removed in the form of a slit or strip 5. This manner of severing has in view the justification of the line by a lessening of the tension of the elastic member 2 as well as by placing it under greater 15 tension, and is adaptable to the justification of a line which is over measure as well as of a line which is under measure. In this latter case the member 2 is placed under a certain degree of tension before the member 1 is 20 fastened thereto, and means for holding it thus under tension until such time as the slits or strips 5 are removed are provided.

In Fig. 9 the characters are shown carried on the elastic element 2. The inelastic element 1 may be separated or slitted inter-
25 verbally if desired.

The mounting of the character-receiving medium upon a support is contemplated by some features of the invention, and by cer-
30 tain features thereof the providing of a support to form a line bar is also contemplated, and in Fig. 6 is shown such a line bar. The bar comprises a supporting member 6 which has fastening means 7 of any approved char-
35 acter at one end, such fastening means being designed to occupy but little space in order that the characters upon the surface may occupy as nearly as possible the full length of the bar. Upon the other end of the bar 40 are provided releasable fastening means of suitable character, such as the adjustable clamping member 8 having a jaw member 9 which takes over and holds the member 3 firmly, as by pressing it against the struc-
45 ture of the supporting member 6. This may be done by means of a spring 10 or by means of a screw member 11, or by any other suitable means.

When desirable, a suitable gage device 50 may be employed, and in the illustrated embodiment the line bar is shown provided with means for indicating the measure to which the composed line is to be justified. This may consist of a gage member 12 hav-
55 ing a finger 13 and a slot 14 through which passes a set screw 15 for holding the gage in any adjusted position. Where the line may be composed long or short with this form of device, the member 2 is placed un-
60 der a certain degree of tension before the member 1 is fastened thereto and the characters of which the line is to consist are placed upon the member 1, either before or after it has been fastened to the member 2.

The slits or strips 5 are then removed and 65 by manipulation of the clamping member 8 the elastic member 2 may be allowed to contract from its previous degree of tension in case the line is over measure, and where the line is under measure it is put under greater 70 tension in order to justify the line to the predetermined measure. Where the line is always composed short there is no need of placing the member 2 under tension before the member 1 is attached thereto. 75

From all the foregoing it will be understood that a character-receiving medium has been provided which is capable of giving a justified line of typographic characters without the use of a previously justified line 80 of types, or where impressions are made letter by letter, without the usual preliminary representation means; that said surface may be of such nature as to admit of reproduction in different ways; that the extension or 85 contraction of the surface takes place in the interverbal spaces without any deformation whatever of the character-bearing portions of the said medium; that said medium is adaptable for use in a line bar or line 90 unit; and that other features and advantages are realized.

While the embodiment of the invention herein shown and described provides for manipulation of the character-receiving me-
95 dium 3 by hand to secure the justification, it will be understood that this may be done by suitable mechanism, and the devices included in the invention may be of such par-
ticular form as to be adapted for use in a 100 machine for performing the various operations thereon automatically, as for instance the composition of the line thereon, the jus-
tification of the line, and the transfer of the justified line to another surface. 105

As instancing a use to which the line bar may be put, it may be provided with an off-
set surface and is then adapted to receive a line from metal types, impressed one at a time or a plurality at a time, and by di-
rect composition or otherwise, to justify same, and then to transfer it as justified to another metal surface which may be prepared as a printing plate. The elastic layer may be of offset material if desired as cer-
115 tain materials possessing the requisite properties are known, such as rubber by way of example. Other character-receiving sur-
faces may be used, however, for instance a transfer surface or a planographic surface, 120 or other suitable surface, as the example given is illustrative only and not restrictive in character.

The invention, in its broader aspects, is not limited to the particular constructions shown, nor to any particular constructions by which it has been or may be carried into effect, as many changes may be made in the 125

construction without departing from the main principles of the invention and without sacrificing its chief advantages.

What I do claim as my invention and desire to secure by Letters Patent, is:

1. A composing device comprising in combination a character-receiving medium, said medium having two layers, one layer being of elastic material and the other of inelastic material, a support for said character-receiving medium, said parts being constructed and arranged so that the character-receiving medium and the support are movable relatively to each other, and means for rendering the said medium and support immovable relatively to each other at a particular point.

2. A composing device comprising in combination a character-receiving medium, said medium having two layers, one layer being of elastic material and the other of inelastic material, and means for holding said elastic layer under tension.

3. The combination with a character receiving line strip, comprising an elastic layer and a continuous inelastic layer of a member for supporting said line strip but the line strip being movable relatively thereto.

4. The combination with a character receiving line strip, comprising an elastic layer and an inelastic layer attached together throughout the line length of a supporting member for the line strip, the line strip and support being movable relatively to each other.

5. A unit of composition comprising a character receiving medium in the form of a strip comprising a layer of elastic material and a layer of inelastic material, one of said layers carrying characters in word groups, said layers being arranged so that the elastic material may contract and expand only between words to vary the length of a line of characters.

6. As a unit of composition a character-receiving medium in the form of a strip comprising a layer of elastic material and a layer of inelastic material, said layer of inelastic material carrying upon its surface a series of characters or groups of characters, and having cuts or slits extending through it between words or syllables, and means for holding the elastic layer under tension so as to vary the space between words.

7. A composing device comprising in combination a character-receiving medium, said medium having two layers, one layer being of elastic material and the other of inelastic material, a gage, and means for holding said elastic layer under tension.

8. A line bar comprising a supporting member, an elastic member carrying an inelastic member and means for holding said elastic member under tension.

9. A line bar comprising a supporting member, an elastic member carried thereby, an inelastic member carried by said elastic member said inelastic member having one or more cuts or slits therethrough, and means carried by said supporting member for holding the elastic member under tension.

10. A line bar comprising a supporting member, an elastic member carried thereby and means for holding said elastic member under tension.

11. A line bar comprising a supporting member, an elastic member carried thereby and means for holding said elastic member under tension, and a gage carried by said supporting member.

12. A line bar comprising a supporting member, an elastic member carried thereby and means for holding said elastic member under tension, and an adjustable gage carried by said supporting member.

13. A line bar comprising a supporting member, an elastic member carried thereby, an inelastic member carried by said elastic member and having on its surface a series of characters or groups of characters and having cuts or slits therethrough between certain characters or groups of characters and means carried by said supporting means for holding said elastic member under a desired degree of tension to which it may be adjusted, for the purpose of justifying the said series of characters.

14. A composition unit having an offset surface for receiving an imprinted line and means for varying the interverbal distances without varying the space or distance occupied by the words to justify the line after it is printed.

In testimony whereof I have signed my name to this specification in the presence of two subscribing witnesses.

GEORGE R. CORNWALL.
